UNITED STATES PATENT OFFICE.

FORTUNAT CHAREST, OF CLOQUET, MINNESOTA.

CLOTHES-LINE.

1,111,563.

Specification of Letters Patent. Patented Sept. 22, 1914.

Application filed January 15, 1914. Serial No. 812,343.

To all whom it may concern:

Be it known that I, FORTUNAT CHAREST, a citizen of the United States, residing at Cloquet, in the county of Carlton and State 5 of Minnesota, have invented certain new and useful Improvements in Clothes-Lines, of which the following is a specification.

My invention relates to an improvement in clothes lines, and the object is to provide 10 means whereby the line can be lowered from the supports to a position where the person hanging the clothes can place the clothes upon the line, and after the clothes have been secured to the line, the line may be 15 elevated to a sufficient height so as to prevent the clothes from being soiled by anyone passing beneath the line.

The invention consists of certain novel 20 features of construction and combinations of parts which will be hereinafter more fully described and pointed out in the claims.

In the accompanying drawings: Figure 1 is a view in side elevation; Fig. 2 is an end view; and Fig. 3 is a detail sectional view 25 showing the manner of mounting the carriage or movable member.

A, A represent two posts, which form the supports for the lines 1, 1. Mounted upon the posts are plates 2, 2 which extend above 30 the upper ends of the posts, and mounted between the plates are pulleys 3, 3. The plates 2 extend beyond the rear sides of the posts for forming guides for the carriages, the carriages consisting of a block B and 35 wheels 4, 4, each block having four wheels, which are adapted to engage the rear sides of the post A and travel thereon. Connected to each block is a cross bar 6, which can be of any desired length, and connected 40 to these cross bars are the lines 1, the lines extending from one cross bar to the other from post to post for forming the necessary strands for supporting the clothes to be hung. A rope or cable 7 is connected to 45 each block B, and passes over a pulley 3 supported by the plates 2. A counter-weight 8 is connected to each rope or cable 7 for maintaining the carriage at the upper ends of the posts.

50 Stops 9, 9 are formed on the plates at the upper ends of the posts, which are adapted to engage the cross bars 6 for limiting the movement of the carriage, and stops 10, 10 are provided on the plates 2 for limiting the 55 downward movement of the carriage. The

carriages carrying the lines can be lowered by simply raising the counterweights 8, so that the carriages, by their own weight, will carry the lines downward within the reach of the person desiring to place the clothes 60 upon the lines, and after the clothes have been placed upon the line, by pulling downward upon the cables 7, the lines can be raised to the desired elevation for such a distance as will prevent any one from coming 65 in contact with the clothes should they pass beneath the lines.

The weight of the lines, when the clothes have been placed thereon will cause the carriages to be brought into closer contact with 70 the poles or posts, so that the carriages can be held at any elevation between the stops but under normal conditions, when the lines are not in use, the counter-weights, which are slightly heavier than the carriages, will 75 cause the carriages to be drawn to the upper ends of the posts, so that the lines will be out of the way and will not interfere with anyone passing between the posts.

I claim:

1. The combination with posts having 80 guide plates mounted thereon, of wheeled carriages, each carriage engaging a side of the post and located between the guide plates, whereby the carriages are maintained 85 in position, counter-weights connected to the carriages for maintaining them upon the posts, cross bars connected to the carriages having lines connected thereto, and stops on the guide plates engaged by the cross bars 90 for limiting the upward and downward movement of the carriages.

2. The combination with posts, of carriages movably mounted thereon, means for normally maintaining the carriages at the 95 upper ends of the posts, cross bars connected to the carriages having lines connected thereto, which lines, when articles are suspended thereon, overcome the effect of the means for maintaining the lines and 100 carriages at the upper ends of the posts by bringing the carriages into engagement with the posts, so that the lines and carriages may be held at any elevation.

In testimony whereof I affix my signature, 105 in the presence of two witnesses.

FORTUNAT CHAREST.

Witnesses:

TRIMBLE DAVIS,
J. A. FESENBECK.
